UNITED STATES PATENT OFFICE

WILLIAM S. HENRY, OF ROCHESTER, NEW YORK, ASSIGNOR TO GENERAL RAILWAY SIGNAL COMPANY, OF ROCHESTER, NEW YORK

INTERLOCKING SYSTEM FOR RAILROADS

Application filed October 5, 1926. Serial No. 139,641.

This invention relates to interlocking systems for railroads, and more particularly to features of cross protection and indication for such systems.

5 In order to simplify the disclosure and description of the present invention the term "traffic controlling device" is used to signify any one of the devices used for controlling the movement of traffic on a railroad such as, a 10 wayside signal, a switch machine, a power operated derail, a power operated movable point frog, and the like.

In one type of central energy all-electric interlocking system, commonly known as a 15 dynamic indication system, the necessary interlocking between the traffic controlling devices may be said to be obtained primarily by the mechanical interlocking between levers controlling said devices and the dynamic indication mechanism, and associated parts, which assure that the position of the lever shall correspond with the position of the traffic controlling device. This dynamic indication type of interlocking system, being well known, need not be discussed 20 in detail; but to facilitate an understanding of the improvements of this invention, it is desirable to note that the dynamic current, in addition to operating the indication mechanism of the levers, also serves to snub the motor of the switch machine, and furthermore checks the integrity of the circuit through the cross protection relays.

Generally speaking, the principal objects 35 of the present invention are to simplify and improve the dynamic indication type of all-electric interlocking system, more particularly by making provisions to permit omission of the indication mechanism on the 40 levers, and associated parts, such as the safety magnet, indication selector, which have been found essential to guard against improper operations of the indication mechanism, while at the same time retaining a reliable 45 check upon the cross protection relay, and utilizing the dynamic current for snubbing. More specifically, it is proposed to eliminate indication positions on the levers, permitting their unrestrained movement, except as they may be locked by detector lock-

ing, or directly by an electrical lever lock, or indirectly through the mechanical locking, in case conflicting levers have not been operated or their respective traffic controlling devices responded, several organizations and arrangements in this respect being possible. In order to indicate in the tower the existing position of the traffic controlling devices, more particularly the position of switch points, to permit interlock or inter-control with conflicting levers, it is proposed to employ a relay in the tower, commonly known as an S. S. relay, energized over a circuit, preferably polarized, which is controlled by contacts operated in accordance with the position of the switch or other traffic controlling device. To check the integrity of the cross protection circuit, a dynamic current responsive device is connected in this circuit; and its contacts, which are included in the energizing circuit 60 for the S. S. relay, and which are automatically opened each time a lever is moved or its corresponding traffic controlling device is operated, will not close and permit energization of the S. S. relay, unless dynamic 65 current actually flows through the cross protection circuit.

One advantageous feature of the improved type of system just described in general terms is that a plurality of switches or signals can 70 conveniently be controlled from a single lever, while retaining the advantages of the dynamic indication central energy type of system.

Other objects, purposes and characteristic 75 features of the invention will in part appear as the description progresses and in part be obvious from the drawings.

In describing the invention in detail reference will be made to the accompanying drawings in which:—

Fig. 1 illustrates the invention applied to a single lever unit for operating the two switch machines of a cross-over, in which the dynamic current responsive relay is mechanically forced to its inactive position by movement of the lever; and Fig. 2 illustrates a modified form of the invention applied to a system similar to that shown in Fig. 1, in which the dynamic current responsive relay is 100

electrically operated to its inactive or abnormal position.

Referring to Fig. 1, an application of the present invention has been illustrated in the control circuits for two switch machines controlled by a single lever L. This lever L is one of a large number of levers in an interlocking plant, where conflicting levers are mechanically interlocking through a suitable interlocking frame including horizontal locking bars which are operated or locked, as the case may be, by vertically operated locking tappets, of which the tappet 10 only has been illustrated. These tappets, as shown, are moved vertically in response to horizontal movement of the levers in any suitable way, as by a roller moving in a slot. It may be explained here that, in the system of this invention, this mechanical interlocking between levers is retained, though not absolutely essential in some forms of the invention for safety, to determine the sequence of operation of the levers, so as to avoid traffic delays on account of failure of the operator to move the number of levers and in the sequence required to set up the desired route. It should be understood, however, that this mechanical interlocking between levers, particularly between switch and signal levers, may be utilized to prevent operation of a lever, for instance a switch lever, until other conflicting levers have been operated and their respective traffic controlling devices responded.

In the particular arrangement illustrated in the drawings, a cross-over track CO has been illustrated connecting a west bound track W and an east bound track E, this cross-over track being provided to permit trains to be transferred from the east bound to the west bound track, or vice versa, when required. Since the switches of this cross-over track CO should always assume corresponding positions it is feasible and desirable to control the two switch machines SM¹ and SM² by the same lever. At the east end of the cross-over have been illustrated a west bound main signal S¹ and a diverging route signal S³, and at the west end of this cross-over have been illustrated on east bound main signal S² and a diverging route signal S⁴. There are of course provided additional distant signals which have for convenience been omitted.

Each of the switch machines are controlled by control circuits including a cross protection relay, and each of these relays CPR¹ and CPR² are constructed to be actuated if direct current flows through the winding thereof in one direction but which will not respond if direct current flows in the other direction. These relays preferably include a permanent magnet 11, soft iron cores 12 and 13, a soft iron armature 14, contacts 15 and a coil 16 contained on the core 12. In this construction the flow of direct current in one direc-

tion in coil 16 causes additional magnetic flux to pass through core 13 and armature 14 to hold the contacts 15 closed; whereas the flow of direct current in the opposite direction in coil 16 robs this core 13 and armature 14 of magnetic flux supplied by the permanent magnet 11 and causes the armature to drop and complete a magnetic circuit through core 12. These cross-protection relays are therefore polar stick relays which if once operated to open their contacts 15 must be mechanically reset.

In each of the control circuits of the switch machines SM¹ and SM² is included a dynamic current responsive relay of the mechanical stick or toggle type. These relays have been designated D¹ and D², and have their armature 20, held in either the raised position, or the lowered position against the stop 28, as the case may be, by the toggle mechanism including the rotatable perforated post 21, a crank arm 22, a guide pin 23, and a spring 24 on said guide pin for holding the crank 22, in one or the other of its extreme positions. It will readily appear that movement of the lever L from either extreme position to the opposite extreme position causes the armatures 20, to be forced to their lower position by the projections on the push rod 25, which rod is returned to its normal position by a spring 26.

In view of the fact that the various devices shown for the purpose of illustrating applicant's invention have been shown in accordance with established convention it is believed expedient to now consider the operation of the system embodying applicant's invention. Let us therefore assume that it is desired to operate both of the switches 18 and 19 to the diverging route position, so as to permit a train to take the cross-over track from one of the main tracks to the other main track. It will at once appear that the lever L cannot be moved until all of the conflicting levers assume a non-conflicting position, this by reason of the mechanical interlocking mechanism including the locking tappet 10. If now all of the conflicting levers have been moved to the proper position, the lever is free to be moved as far as the mechanical interlocking is concerned. Also if there is no train standing on any of the detector track circuits associated with the main tracks and cross-over track, or on the approach locking track circuits if such are used, all depending on the exact construction of the detector and approach locking arrangement, the various track relays such as T⁵, T⁶, T⁷ and T⁸ will assume their energized positions. Also, if all of the various conflicting traffic controlling devices assume the proper position and have responded to the last change in the position of their control lever, their corresponding indication relays and dynamic current responsive devices will assume the proper position to

unlock the lever L. These indication relays and dynamic current responsive devices have been generally illustrated by the relay IR⁹ and the dynamic current responsive devices D^x and D^y, respectively. In this event the energizing circuit for the lock magnet LM which constitutes a lever lock is energized through a circuit readily traced in the drawings and the lever L may be moved to the reverse position.

In the case where a conflicting traffic controlling device constitutes a signal, its control lever may be provided with a lever lock magnet, which permits it only to be moved to the half normal position, and this magnet may be controlled by a circuit including a contact on the signal closed when the signal is at stop, all as well understood by those skilled in this art. By this arrangement this signal lever through the mechanical interlocking will afford the necessary locking.

The movement of the lever L to the reverse position causes the armatures of the dynamic current responsive relays D¹ and D² to assume a position to open their contacts 27¹ and 27², these contacts being held open by the toggle springs 24. With the lever L assuming the reverse position the following circuit is completed for the switch machine SM¹—beginning at the battery 30, wires 31, 32, 33, 34, contacts 35—36, wire 37, reverse wire R¹, contacts 39—40, wires 41 and 42, armature of the motor M¹, wires 43 and 44, contacts 45—46, wire 47, field winding of the motor M¹, wires 48, 49 and 50, contacts 15 of the cross protection relay CPR¹, wire 51, contacts 15 of the cross protection relay CPR², wire 52, back to battery 30. Another circuit similar to the one just traced is completed for the switch machine SM² which circuit need not be specifically traced. The completion of these circuits causes the motors M¹ and M² to be operated, thereby moving the track switches 18 and 19 to the cross-over position. When the motor M¹ has completed the stroke of the switch machine SM¹ the contacts 40 and 46 of this switch machine will be quickly moved to the dotted position and by such movement will reverse the relation of the connections between the field and the armature of the motor M¹, thereby causing a snubbing current to be generated which retards or brakes the motor.

This current flows in the following circuit and returns the armature 20 of the dynamic current responsive relay D¹ to its raised position: beginning at the armature of motor M¹, wire 42, contacts 53—46, wire 54, field of motor M¹, wires 48, 49 and 55, winding 16 of the cross protection relay CPR¹, wire 56, winding of the dynamic current responsive relay D¹, wire 57, contacts 58—59, wire 60, normal wire N¹, contacts 61—40, wires 43 back to the armature of the motor M¹.

65 This dynamically generated snubbing cur-

rent flows through the coil 16 of the cross protection relay CPR¹ in such a direction as not to operate armature 14 of this relay, and flows through the dynamic current responsive relay D¹ to cause the armature 20 to assume the raised position so as to close the contacts 27¹. In a similar way the operation of the motor M² and its snubbing action causes the armature 20 of the dynamic current responsive relay D² to assume its raised position.

With the switch machine SM¹ and SM² assuming the reversed position, the indication relay IR¹ and IR² will assume the reversed position, because the contacts 62 associated with the switch machines SM¹ and SM² have reversed the polarity of the current applied to these indication relays. By reason of the simplicity of the circuits for these indication relays IR¹ and IR² it is believed unnecessary to trace the circuits therefor. It should, however, be noted that the circuit for indication relay IR¹ includes in series therewith the contact 27¹ of dynamic current responsive relay D¹, and the circuit for the indication relay IR² includes in series therewith the contact 27² of the dynamic current responsive relay D². In other words, the relays IR¹ and IR² cannot assume an energized position unless the contacts of their corresponding dynamic current responsive relays have been closed. It may be pointed out at this time that the contact 62 is open so long as the switch machine with which it is associated is unlocked; this switch machine preferably being one of the type shown in the patent to Howe No. 1,466,903.

The switches 18 and 19 now having been moved to the cross-over or diverging route position and the indication relays IR¹ and IR² having assumed their reverse position, electrical energy is applied to the wire 65 from a suitable source of energy having a terminal B through contacts 66 and 67 in their dotted position. This wire 65 preferably leads to the levers of diverging route signals such as the signals S³ and S⁴ shown, from which it appears that these diverging route signals cannot be cleared until the switches 18 and 19 assume the cross-over position. Likewise, it is apparent that the main signals such as the signals S¹ and S² cannot be cleared until the terminal B is connected to the wire 68 which leads to the levers of the main signals, and which requires the contacts 66 and 69 to assume their normal right hand position, in which they have been shown.

By examining the circuit arrangement of the switch machines SM¹ and SM² it will readily appear that the cross protection relay CPR¹ is connected in multiple with the motor M¹ for all cases where it is possible for unauthorized current to be applied to this motor, and that the cross protection relay CPR² in like manner is connected in multiple

with the motor M^2 , and that this is true regardless of whether these switch machines assume the normal straight track position or the reverse diverging route position. This arrangement of devices and circuits is resort to so that if current should be applied to one or the other of these motors accidentally by reason of a cross, or the like, this current would be permitted to flow through two paths, one of which is of a medium resistance, namely that of the motor of the switch machine, and the other of which is of extremely low resistance, namely that including the dynamic current responsive relay D and the winding 16 of the cross protection relay in series, so that a large part of the current due to such cross will flow through these two relays. Also, it should be noted that this flow of current would be from wire 56 toward wire 55 through the coil 16 of the cross protection relay. Current flow in this direction causes the cross protection relay to respond and open its contact 15, thereby disconnecting the negative side of the battery 30 from the common return wire 49. In practice it has been found that this will occur before the motor of the switch machine has had time to start moving the switch.

The partial cross protection branch circuit just mentioned, including the dynamic current responsive relay D and the cross protection relay CPR , is in multiple with the motor of the switch machine, and therefore if this branch circuit should accidentally become open, the cross protection relay CPR would not respond to this flow of unauthorized current, and for this reason it is important that the continuity of this branch circuit be checked repeatedly.

In accordance with the present invention, the continuity of this branch circuit is checked for each operation of the traffic controlling device, which device in the particular arrangement shown comprises a switch machine, by requiring a flow of snubbing or dynamic current in this branch circuit before the circuit for the corresponding indication relay is completed, so that the flow of snubbing current not only retards the motor but also manifests the integrity of the branch circuit including the cross protection relay. This dynamic snubbing current also manifests that the traffic controlling device has responded to the last movement of the control lever. In this connection it is desired to point out that for those traffic controlling devices in which only one position thereof need be indicated, such as a signal for instance, (the danger condition of which only need be indicated at the tower), and wherein the indication relay may be a two position relay, the indication circuit leading to the traffic controlling device may be entirely dispensed with and the dynamic current responsive relay itself may be used as

an indication relay, or it may be connected to control an indication relay either by itself or in conjunction with other relays, all as obvious to those skilled in the art of interlocking after reading the foregoing description. 70

Movement of the lever back to its normal position in which it has been shown, establishes the normal circuit including the wire N^1 , which is substantially the same as the reversed circuit including the wire R^1 , and for this reason it is deemed unnecessary to specifically trace the normal circuit or the normal branch circuit which as shown in the drawing includes the dynamic current responsive relay and cross protection relay in series. 75 80

If the invention illustrated in Fig. 1 is applied to the traffic controlling device having only one important position, such as a signal as shown in the patent to Benedict No. 1,533,357, the lever L would only be provided with one notch for operating the push rod 25, this notch being so positioned and constructed that the push rod 25 is depressed 90 when the lever is moved to a position to clear the signal, but is not depressed when the lever is returned to normal. By this arrangement the dynamic current responsive relay D would be returned to normal by snubbing current 95 when the signal is returned to the normal danger position.

As readily appears from the drawing, the present invention permits any number of traffic controlling devices to be operated or controlled by the same lever, because each traffic controlling device may have its own indication relay and these indication relays may have their contacts so connected that conflicting traffic controlling devices may be 105 prevented from being operated until all of the traffic controlling devices controlled by such single lever have responded. Also, each of these traffic controlling devices, although controlled by a single lever, may have their 110 individual circuits provided with cross protection relays; and the integrity of the branch circuit including such relay is checked for each operation of the traffic controlling device. 115

In the present invention the dynamic current responsive device serves two important functions (1) it manifests after each operation of the traffic controlling device that the branch circuit including the cross protection relay is intact, and (2) it manifests that the traffic controlling device has actually responded to the last change in the position of the lever for controlling such device, because the contact of such dynamic current responsive device is opened during each lever movement and dynamic current must have flowed and reclosed such contact. In addition to these features the circuit for the snub- 120 125 130

bing current permits the motor to be electrically braked or snubbed.

In order to indicate whether or not the switch machines SM^1 and SM^2 assume an extreme position and whether the dynamic current responsive relays D^1 and D^2 assume the attracted or retracted position indication lamps P^1 and P^2 have been provided. Each of these lamps is energized when its corresponding switch machine assumes an extreme position and its corresponding dynamic current relay is in the retracted position as is obvious from Fig. 1 of the drawings.

In Fig. 2 of the drawings has been illustrated a layout including two switches operated by switch machines which are controlled in exactly the same manner as are the switch machines shown in Fig. 1, except that the dynamic current responsive relays, which have been designated DS^1 and DS^2 in Fig. 2 of the drawings are electrically operated to their abnormal or non-indicating position, whereas the dynamic current responsive relays D^1 and D^2 of Fig. 1 are mechanically operated to their non-indicating positions. Referring to these two drawings it should be noted that the coil 70 of the dynamic current responsive relay DS^1 is connected in series with the coil 16 of the cross protection relay CPR^1 exactly in the same way as is the winding of the dynamic current responsive relay D^1 in Fig. 1 of the drawings. Also, it should be noted that the coil 71 of the dynamic current responsive relay DS^1 (see Fig. 2) is connected in the wire 33 of the circuit arrangement shown in Fig. 1, and for this reason the wires leading to and from the coils 71 of the dynamic current responsive relay DS^1 have been designated 33^a and 33^b in Fig. 2 of the drawings. In this connection, it should be noted that if the contact 27^a of the dynamic current responsive relay DS^1 , is in the left hand position it will shunt the winding 71 of this relay. The construction of a device suitable for these dynamic current responsive relays DS^1 and DS^2 of Fig. 2 is shown in the patent to W. K. Howe, No. 1,550,611, dated August 18, 1925.

In order to more clearly understand how the dynamic current responsive relay of Fig. 2 is caused to assume its abnormal position upon movement of the lever, and how movement of this contact is assured before the traffic controlling device can respond to a change in the position of its control lever, it is deemed expedient to go through the various steps of operating a traffic controlling device to the reverse position and receiving an indication that it has been operated to such position. Referring to Fig. 2 let us assume that the various indication relays IR , the various track relays T^6 , T^6 , T^7 , T^8 and the various dynamic current responsive relays DS^x and DS^y all assume a position to close their contacts so that the lock magnet

LM of the lever L is energized and permits movement of the lever from its normal to its reverse position.

Movement of the lever L to its reverse position causes the following circuit to be completed:—beginning at the battery 30, wires 31, 32, and 33^a, winding 71, of the dynamic current responsive relay DS^1 , wire 33^b, wire 34, contacts 35—36, wire 37, reverse wire R^1 , contacts 39—40, wires 41 and 42, armature of the motor M^1 , wires 43 and 44, contacts 45—46, wire 47, field winding of the motor M^1 , wire 48, common return wire 49, wire 50, contact 15 of the cross protection relay CPR^1 , wire 51, contact 15 of the cross protection relay CPR^2 , wire 52 back to the battery 30.

The completion of this circuit causes the current to flow through the magnet coil 71 of the dynamic current responsive relay DS^1 , but by reason of the high resistance of the coil 71 the motor M^1 will not be operated the instant this circuit is completed. The flow of current in the coil 71 will however, cause the contacts 27^a of the mechanical stick dynamic current responsive relay to be shifted to the left hand position where it will be frictionally and latching held, and this shifting of the contact 27^a causes the coil 71 to be shunted, thereby permitting a heavier current flow which will operate the motor M^1 of the switch machine SM^1 . Operation of the switch machine SM^1 to its reverse, or cross-over position, causes the contacts 62 to shift thereby reversing the polarity applied to the indication circuit, the indication relay IR^1 will however remain in its de-energized position because its energized circuit has been opened at the contact 27^a of the dynamic current responsive relay DS^1 . Also, when the motor of the switch machine SM^1 has completed its operating stroke, the contacts 40 and 46 are very quickly shifted to the reverse position, whereby the relation of the field to the armature of the motor M^1 is reversed, thereby causing the motor to act as a generator and causing a heavy snubbing current to flow in the following circuit:—beginning at the armature of the motor M^1 , wire 42, contacts 53—46, wire 54, field winding of the motor M^1 , wire 48, common return wire 49, wire 55, winding 16 of the cross protection relay CPR^1 , wire 56, winding 70 of the dynamic current responsive relay DS^1 , wire 57, contacts 58—59, wire 60, normal wire N^1 , contact 61—40, wire 43, back to the armature of the motor M^1 .

The flow of snubbing current in this snubbing circuit causes the magnet 70 of the dynamic current responsive relay DS^1 to return the contact 27^a to its normal right hand position, in which the energizing circuit for the indication relay IR^1 is completed, thus causing this relay IR^1 to assume the reverse dotted position. In like manner, the operation of the lever L causes the switch machine

SM² to be operated in the same way and in turn cause the indication relay IR² to assume the reverse position, so that electrical energy is applied to the levers of diverging route signals in a manner as explained in connection with Fig. 1 of the drawings.

In order to indicate to the operator when the traffic controlling device has responded to a change in the position of the lever (see Fig. 2) the indicating lamps J¹ and K¹ may be used if desired. These lamps J¹ and K¹ are respectively energized when the dynamic current responsive relay DS¹ assumes the normal and abnormal position, respectively, these energizing circuits being readily traced and include contact 74 of the relay DS¹ and the terminals B and C of a suitable source of current. Similar indicating lamps J² and K² are shown in connection with the relay DS².

It is thus noted that in the arrangement shown in Fig. 2 of the drawings, movement of the contacts 27^a of the dynamic current responsive devices DS¹ and DS² to the left hand abnormal position in response to movement 25 of the lever is assured, because the switch machine motors cannot operate so long as the coil 71 of high resistance is connected in series therewith, and the fact that this coil 71 is shunted by the contact 27^a is proof that this contact 27^a has been shifted to its abnormal position. The features of cross protection, checking of the cross protection branch circuit and checking of the indication of the arrangement shown in Fig. 2 is identically the same as that of the arrangement shown in Fig. 1, and for this reason a further discussion of the arrangement shown in Fig. 2 is deemed unnecessary. It may, however, be pointed out that the arrangement shown in Fig. 2 has certain advantages in that the dynamic current responsive devices are self contained and need not be mechanically connected with the lever with which they are associated. Also, it may be pointed out that, if the arrangement shown in Fig. 2 is employed for operating a signal, the coil 71 would be connected in the operating wire of a signal circuit such as shown in the patent to Benedict above referred to, and the coil 70 would be substituted in the circuit for the indication magnet IM in said patent.

Having thus shown several embodiments of the present invention applied to a combination wherein two switch machines are operated by the same lever, it is desired to be understood that this has been done to bring out the advantages of the present invention which makes it especially well applicable to an arrangement wherein a plurality of traffic controlling devices are controlled by a single lever, but that the invention may be applied to an arrangement where a single traffic controlling device is controlled by a lever with substantially the same advantages. Also, it is desired to be understood

that the invention is applicable to control circuits for controlling any suitable traffic controlling device irrespective of whether it has only one essential position, as does a signal, or whether it has several essential positions, as does a switch machine, and that the various indication relays may prevent the operation of conflicting traffic controlling devices either by controlling a lock magnet, as has been shown in connection with the lever L, or by controlling the main operating circuit leading to the traffic controlling device itself, as illustrated by the circuits including contacts 66, 67 and 69. In other words, it is desired to be understood that, although several specific arrangements have been shown, the arrangements shown are susceptible of modification and adaptation to the particular interlocking problem encountered without departing from the scope of the invention.

What I desire to secure by Letters Patent, is:—

1. In an interlocking system for railroads, a traffic controlling device including a motor for operating the same, a lever for applying operating current to said motor, an indicating device for indicating the condition of said traffic control device, an indicating circuit for energizing said indicating device, a circuit for snubbing said motor completed when said motor has completed the operating stroke of said traffic controlling device, and means for breaking said indicating circuit when said lever is operated and maintain it broken unless current flows in said snubbing circuit after said motor has completed such operating stroke.

2. In an interlocking system for railroads, a traffic controlling device including a motor for operating the same, a lever for applying operating current to said motor, an indicating device for indicating the condition of said traffic controlling device, an indicating circuit for energizing said indicating device, a circuit for snubbing said motor completed when said motor has completed the operating stroke of said traffic controlling device, and dynamic current responsive means contained in said snubbing circuit and having contacts closed in response to the flow of snubbing current in said snubbing circuit and opened in response to operation of said lever, said contacts being contained in said indicating circuit, whereby said indicating circuit is opened at said contacts upon operation of said lever and is reclosed in response to the flow of snubbing current in said circuit.

3. An interlocking system for railroads, the combination with a single lever, of two motor operated traffic controlling devices controlled by said lever by independent control circuits, a dynamic current responsive device in each of said control circuits which assumes an energized condition in response to current dy-

namically generated by said motor after said motor has completed the operating stroke of said traffic controlling device, a pair of contacts for and controlled by each of said dynamic current responsive devices, and a circuit for a conflicting traffic controlling device including both of said pairs of contacts.

4. In an interlocking system for railroads, the combination with a single lever, of two motor operated traffic controlling devices controlled by said lever by independent control circuits, a dynamic current responsive device in each of said control circuits, each device assuming an energized condition in response to current dynamically generated by the corresponding motor after such motor has completed the operating movement of said traffic control device, an indicating relay for each of said traffic control devices controlled by an indicating circuit controller located at and responsive to the operated condition of such traffic controlling device, contacts controlled by one of said dynamic current responsive devices contained in one of said indicating circuits, and contacts controlled by the other of said dynamic current responsive devices contained in the other of said indicating circuits.

5. In an interlocking system for railroads, the combination with a traffic controlling device, a motor for operating said traffic controlling device, a cross protection relay at times connected in a branch circuit in multiple with said motor, an indicating device for indicating the operated position of said traffic controlling device controlled by an indicating circuit including a pair of contacts controlled by said traffic controlling device, dynamic current responsive means contained in said branch circuit for checking the integrity of said branch circuit, and contacts controlled by said dynamic current responsive means for interrupting said indicating circuit unless said dynamic current responsive means responds after operation of said motor to snubbing current flowing in said branch circuit, whereby the integrity of said branch circuit is checked during each operation of said motor, and whereby the completion of the indicating circuit requires closure of the contacts controlled by said traffic controlling device and closure of the contacts controlled by said dynamic current responsive means.

55 6. In an interlocking system for railroads, the combination with a traffic controlling device, a motor for operating said traffic controlling device, a cross protection relay at times connected in a branch circuit in multiple with said motor, an indicating device for indicating the operated position of said traffic controlling device controlled by an indicating circuit including a pair of contacts controlled by said traffic controlling device, another pair of contacts in said indi-

cating circuit, a coil for opening said another pair of contacts contained in the energizing circuit of said motor during operation of said motor, another coil for closing said another pair of contacts connected in series with said motor during snubbing action of said motor, whereby said indicating device cannot assume its energized condition unless the contacts controlled by said traffic controlling device are closed and a dynamic current has been flowing in said another coil since the last operation of said motor.

7. In an interlocking system for railroads, the combination with a traffic controlling device, a motor for operating said traffic controlling device, a cross protection relay at times connected in a branch circuit in multiple with said motor, an indicating device for indicating the operated position of said traffic controlling device controlled by an indicating circuit including a pair of contacts controlled by said traffic controlling device, another pair of contacts in said indicating circuit, a coil for opening said another pair of contacts contained in the energizing circuit of said motor during operation of said motor, another coil for closing said another pair of contacts connected in series with said motor during snubbing action of said motor and means controlled by said first mentioned coil for shunting said first mentioned coil upon application of current to said motor, whereby said indicating device cannot assume its energized condition unless the contacts controlled by the said traffic controlling device are closed and a dynamic current has been flowing in said another coil since the last operation of said motor.

8. In an interlocking system for railroads, the combination with a traffic controlling device, a motor for operating said traffic controlling device, a cross protection relay at times connected in a branch circuit in multiple with said motor, an indicating device for indicating the operated position of said traffic controlling device controlled by an indicating circuit including a circuit controller operated by said traffic controlling device, a pair of contacts in said indicating circuit, a coil for opening said a pair of contacts, said coil being included in the energizing circuit of said motor during operation of said motor, another coil for closing said a pair of contacts and connected in series with said motor during snubbing action of said motor, and shunting contacts controlled by said first mentioned coil for shunting the same upon the application of current to said motor, the resistance of said first mentioned coil being such as to prevent operation of said motor until said first mentioned coil has operated the shunting contacts, whereby said motor cannot be operated unless said first mentioned coil has been shunted and said a pair of contacts have been opened, and whereby said in-

dicating device cannot assume its energized condition unless the circuit controller operated by said traffic controlling device has changed and a dynamic current has been flowing in said another coil since the last 5 operation of said motor.

9. In an electric interlocking system of the central energy type, a traffic controlled device having an operating motor, a lever controlling the operation of said device, an indicating relay in the tower, a polarized indication circuit for controlling said relay, contacts operated by said traffic controlling device for governing said circuit, means automatically 10 interrupting said circuit upon movement of the lever, and means automatically operated by current generated dynamically by said motor after operation of the traffic controlling device for reclosing said circuit.

10. In an electric interlocking system, a motor operated traffic controlling device, a lever controlling the application of current to said motor, a three position relay in the tower for indicating the position of said device, a polarized indication circuit for controlling said relay, a circuit controller operated by said device for governing said circuit, and electrically operable circuit controlling means associated with said lever for 15 interrupting said indication circuit upon movement of said lever and prior to the application of operating current to the motor, said means acting to reclose said circuit after the motor has completed the movement of said 20 traffic controlling device.

11. In an electric interlocking system, a traffic controlling device having an operating motor, a lever, operating circuits for said motor governed by said lever, said motor being 25 included in a closed snubbing circuit after each operation of the traffic controlling device, a cross protection device included in said closed snubbing circuit and responsive to the direction of current flow therein, contacts 30 closed in the event current of one polarity flows in said snubbing circuit but not closed in the event current flow of the opposite polarity therein, and a separate polarized indication circuit controlled by the position of 35 said traffic controlling device and said contacts.

12. In an electric interlocking system, the combination with a traffic controlling device having an operating motor, of a polarized indication circuit governed by the position of 40 said device, a circuit controller included in said circuit, operating and snubbing circuits for the motor, and coils included in said respective circuits for opening and closing said 45 circuit controller.

13. In an electric interlocking system, a track switch, a reversible motor for moving said switch, operating and snubbing circuits for the motor alternately established during 50 movement of the switch, a separate indication

55 circuit controlled by the position of the switch, and circuit controlling means including a movable element shifted to opposite positions by current in said operating and said snubbing circuits respectively for opening 70 and closing said indication circuit.

In testimony whereof I affix my signature.

WILLIAM S. HENRY.
